CALL DISTRIBUTING SYSTEM

John Wicks, Oak Park, Ill., assignor to Associated
Electric Laboratories, Inc., Chicago, Ill., a cor-
poration of Delaware

Application September 20, 1937, Serial No. 164,639

19 Claims. (Cl. 179—27)

The present invention relates to a call distributing system, and is concerned more particularly with such systems of the above-named character as are used to provide increased trunking efficiency between an A board in one manual exchange and a B board in another manual exchange.

The main object of the invention is the production of a new and improved call distributing system utilizing primary and secondary selector switches to distribute the traffic to available cord circuits at the B operators' positions.

Another object is the production of suitable circuit arrangements whereby all of the cord circuits at a particular B operator's position are made busy during the time required for her to set up a connection received over one of her cord circuits. With this arrangement, calls from A operators control the primary selectors to select idle secondary selectors in connection with cord circuits in other B operators' positions during the time that the cord circuits at one of the positions have been busied.

Another object is the production of suitable circuit arrangements whereby the secondary selector switches are divided into groups and are controlled by means of a chain circuit common to the group, to preselect idle cord circuits only when a predetermined number of the idle secondary selectors in the group are standing on bank contracts connected to busy cord circuits.

The foregoing objects together with others not specifically mentioned at this time will be best understood from the detailed description of the trunking layout and the operation of the various circuits.

Referring to the drawings, Fig. 1 is a schematic diagram showing the trunking arrangement between an A board located in one manual office and the B board located in another manual office, while Fig. 2 is a circuit diagram showing the apparatus required for a system of the type shown in Fig. 1. Only such switching apparatus and circuits as directly concern the invention have been shown in detail in order to avoid unnecessarily complicating the description.

The general system of trunking from the A board in one manual office to the B board in the second manual office will first be briefly explained. Referring to Fig. 1, the jacks at the A board, shown at the left-hand side of the drawing, represent only a portion of the jacks at positions 1 and 2. The jacks JK—1, JK—2, and JK—3 of the position 1 are connected to trunk lines T—1, T—3, and T—5, respectively, while jacks JK—1, JK—2,

and JK—3 of position 2 are connected to trunk lines T—2, T—4, and T—6, respectively. These jacks are multiplied in a certain number of other positions of the A board as indicated by the diagonal line at the right of the jacks. The trunk lines T—1 to T—6, inclusive, are regular two-conductor trunk lines extending between the telephone exchange in which the A board is located and the exchange in which the B board is located. These trunk lines are directly connected to primary selectors PS—1 to PS—6, respectively, which switches are of the well-known rotary line switch type having a capacity of twenty-five lines outgoing from each of their banks. The primary selectors are divided into groups, such as groups 1, 2, and 3, and the trunks, such as 11, 12, and 13, which represent a portion of the trunks from group 1, are multiplied in the banks of all the primary selectors in group 1 and terminate in secondary selector switches, such as secondary selector switches SS—1, SS—2, and SS—3. Outgoing trunks 14, 15, and 16, which represent a portion of the trunks from group 2, comprising primary selectors PS—3 and PS—4, and are multiplied in the banks of all of the primary selector switches in group 2. These trunks terminate in secondary selector switches, such as SS—4, SS—5, and SS—6 located in group 2 of the secondary selector switches. The primary selector switches in group 3, of which switches PS—5 and PS—6 are shown, are wired and multiplied in the same manner described in connection with primary groups 1 and 2.

The trunks from secondary selector switch SS—1 are multiplied in the banks of all of the secondary switches in group 1 and are terminated in an IDF. Only four of these trunks are shown, namely, trunks 20, 21, 22, and 23. The trunks, such as trunks 24 to 27, from secondary selector SS—4 are multiplied in the banks of all of the secondary selectors in group 2 and are terminated in the IDF in the same manner as described in connection with the trunks of group 1. Four positions of the B board are indicated at the right-hand side of the drawings, each of which shows lines indicating three of the plurality of cord circuits in each position of the B operator's board. In order to distribute the traffic from the various groups of secondary selectors, trunks 20 to 23, inclusive, are cross-connected at the IDF in such a manner that the trunk 20 is connected to the first cord in the first position of the B operator's board. Trunk 21 is cross-connected to the first cord in the second position, trunk 22 is cross-connected to the first cord in the third posi-

tion, while trunk 23 is cross connected to the first cord in the fourth position. The same is true of the trunks of group 2 of the secondary selectors, wherein trunks 24 to 27, inclusive, are cross-connected to cords 2 of positions 1, 2, 3, and 4, respectively, of the B board.

The foregoing explanation of the trunking arrangement is only considered between two offices in a manual system. There will necessarily be a similar system of trunking extending between the A board to each of the other manual offices as is the usual practice.

Fig. 2 shows jacks JK-1 of A board positions 1 and 2 connected to trunk lines T-1 and T-2, respectively, which trunks terminate in the primary selector switches PS-1 and PS-2, respectively, located in the same office with the B board. The primary selectors have access to a plurality of trunk lines extending to a plurality of secondary selectors, such as SS-1 and SS-2. However, only one of such trunk lines has been shown terminating in the banks of the primary selectors PS-1 and PS-2. The secondary selectors, such as SS-1 and SS-2, have access to the trunk lines terminating in cord circuits, such as CC-1 and CC-2, or position 1 of the B board. These trunk lines, only one of which is shown connected to the banks of each of the secondary selector switches, pass through an intermediate distributing frame, IDF, and are cross-connected to the cord circuits of the various operators' positions in accordance with the traffic conditions in the B board. Only such apparatus and circuits as are required to describe the invention have been shown and it should be understood that any type of cord circuit can be used incorporating the modifications shown on the drawings. The space shown between the two horizontal dash lines near the lower portion of the drawing indicates other primary and secondary selector switches of group 1, together with associated A board jacks and B board cord circuits. The equipment shown below the bottom dash line is the common relay equipment at the B board.

The primary and secondary selector switches PS and SS of Fig. 2, are mechanically of the well-known rotary type of switch of which the wipers have no normal position and move in a forward direction only. Furthermore, the rotary switch mechanism is of the type arranged to advance its wipers upon each deenergization of the operating magnet.

It is believed that the foregoing brief description of the trunking arrangement between the A board and one manual office and the B board in another manual office is sufficient for a clear understanding of the general layout of the system. The method of operation and the circuits involved will be fully described in the detailed specification, which is to follow.

As is well known in telephone practice, the straightforward method of trunking does not require the use of any order wire between an A board in one manual office and the B board in another manual office due to the fact that the conversation between the two operators is carried on over the trunk selected by the calling A operator.

In order to explain the establishment of a connection between the manual A operator in one exchange and the B operator in another exchange, it will be assumed that the A operator at position 1, Fig. 2, has received a call from a subscriber who desires to extend a connection to a subscriber located in the exchange area served

by the manual office in which the particular B board is located. In addition, it will further be assumed that the operator in selecting a trunk to the wanted exchange has inserted the calling end of her cord circuit into the jack JK-1, which jack is connected to the trunk line T-1. When the calling plug of the A operator's cord circuit is inserted into the jack JK-1, a battery potential is applied to the sleeve of the jack, thereby energizing the sleeve relay 201.

The energization of the sleeve relay 201 closes an obvious circuit for lighting the trunk lamp associated with the jack JK-1. Due to the fact that the conductors of the trunk line and the sleeve relay connected to the jack JK-1 are multiplied to other operator's positions, the sleeve relays associated with the jacks at these multiplied positions are operated and light their associated lamps to inform the operators at these positions that this trunk line is busy.

As a further result of the insertion of the plug of the cord circuit into the jack JK-1, a loop circuit is completed by way of the two conductors of the trunk line T-1, the normally closed contacts of armatures 204 and 205 of the primary selector PS-1, and the winding of the line relay 206. The A operator's cord circuit is provided with the well-known supervisory relay, which is bridged across the tip and ring conductors of the cord circuit and is connected by way of its two windings in series with line relay 206 over the above-traced circuit. However, due to the high resistance of line relay 206, the supervisory relay in the cord circuit is not energized, but sufficient current flows in this circuit to permit line relay 206 to energize.

The energization of relay 206, which is the line relay of the primary selecting switch PS-1 terminating the trunk line T-1 in the B board manual office, causes the initiation of the trunk selecting movement of this switch whereby an idle trunk extending to an idle secondary selecting switch is selected. Upon attracting its armature 208, relay 206 completes a circuit including the winding of the switching relay 202 and the rotary magnet 235 in series. At the same time this circuit is closed, the test wiper 211 is connected by way of armature 203 and its resting contact, armature 207 and its front contact, to a point midway between relay 202 and the rotary magnet 235. The operation now depends upon whether the test contact which the test wiper 211 is in engagement with is busy or not. If this test contact is busy, there will be a ground potential applied thereto and the switching relay 202 will be short-circuited in an obvious manner. At the same time the rotary magnet 235, being supplied with direct ground by way of the test wiper 211 and the engaged busy test contact, will begin operating to rotate the wipers 209, 210, and 211, step by step in search of an idle trunk line extending to an idle secondary selecting switch, such as SS-1. This automatic advancement of the wipers of a rotary switch of this type is the usual operation that takes place when its wipers are engaged with the contacts of a trunk line which is busy. However, in the present case we may assume that when the operation of line relay 206 of the primary selector switch PS-1 takes place, its wipers are standing upon the contacts which are connected to trunk conductors 212, 213, and 214, as shown in the drawings, and we may also assume that this trunk line is idle at the same time.

When the circuit of the switching relay 202 is

completed through the rotary magnet 235, under the above-assumed condition, the switching relay 202 will not be short-circuited and the rotary magnet 235 will not operate in series with the high resistance of the switching relay 202. The switching relay 202, however, is energized, with the following results: At the back contacts of armature 203, it disconnects the previously described shunting circuit for the switching relay 202 and at the front contact of this armature, it connects ground potential from armature 208 to the test conductor 214 of the trunk line extending to the secondary selector switch SS-1 by way of the test wiper 211. Furthermore, this ground potential is also applied to the test contacts in the banks of the primary selector switches to which trunk conductors 212, 213, and 214 are multiplied for the purpose of preventing other primary selector switches from seizing the trunk line which is now engaged by the primary selector switch PS-1. A further result of the grounding of conductor 214 is to provide a temporary holding potential for the lower winding of the line relay 215 in the secondary selecting switch SS-1. At the back contacts of armatures 204 and 205, switching relay 202 disconnects the two conductors of the trunk line T-1 from the winding of line relay and at the front contacts of these armatures the trunk line is extended by way of wipers 209 and 210 to the outgoing trunk line conductors 212 and 213. The line relay 206 in addition to being somewhat slow in energizing when its circuit is closed is also slow to release when the circuit through its winding is opened. Therefore, the ground potential applied to the test wiper 211 by way of armature 208 is not disconnected until the secondary selector switch SS-1 has had time to operate and select a cord circuit in the B board.

It will be seen that the line relay 215 of the secondary selector switch SS-1 is normally bridged across the line conductors 212 and 213 by way of the normally closed contacts controlled by armature 217. Therefore, when the trunk line T-1 of the A board operator's position is transferred from the winding of the line relay 206 of the primary selector switch PS-1 to the line conductors 212 and 213 by the operation of the switching relay 202, the upper winding of line relay 215 is energized over a loop circuit including the A operator's cord circuit. The upper winding of line relay 215 is of sufficiently high resistance to prevent the operation of the supervisory relay in the A operator's cord circuit. However, the line relay 215 energizes and closes the X contact of armature 216, which contact closes before armature 217 closes its front contact to disconnect the circuit for the upper winding of relay 215. The ground potential applied to test conductor 214 now completes a locking circuit for the lower winding of relay 215, while at the normally closed contacts controlled by armature 217, the line conductor 212 is disconnected from the upper winding of line relay 215 and connected by way of the front contact of armature 217 to the wiper 222.

It may be well to mention at this time that the secondary selector switches, such as SS-1 and SS-2, are not accessible to the primary selector switches when the cord circuits that the wipers of the secondary selector switches are engaged with, are busy. When the wipers of the secondary selector switch, such as SS-1 are engaged with a busy cord circuit, a ground potential is applied to the test conductor 214 by way of a

wiper 224. For example, when the cord circuit CC-1 is engaged by another secondary selector switch, for example, the secondary selector switch SS-2, by way of the bank multiple wiring, ground potential is returned from armature 231 in the cord circuit CC-1, normally closed controlled by armature 254, jumpered to the trunk conductor 225 at the IDF, test wiper 224 of the secondary selector switch SS-1, to test conductor 214 and the multiplied test contacts of the primary selector switches. This ground potential applied to the test bank contacts accessible to the wiper 211 of the primary selector switch prevents the seizure of secondary selector switch SS-1 whose wipers are standing on bank contacts of a busy cord circuit. Accordingly, the primary selecting switch will automatically rotate its wipers in the previously described self-interrupting circuit until its wipers engage a trunk line extending to a secondary selector switch whose wipers are standing on a trunk line of an idle cord circuit in the B operator's switchboard.

It has been assumed in the description thus far of the operation of the secondary selector switch SS-1 that its wipers are engaged with trunk line conductors 226-229, inclusive, of a cord circuit that is not busily engaged. Therefore, when the line relay 215 energizes and switches the trunk line conductors 212 and 213 through to the wipers 222 and 223, the circuit is further extended by way of the bank contacts of these wipers, conductors 226 and 227, jumpers of the IDF, to the lower left-hand and right-hand windings of the repeating coil R1, to the upper and lower windings of line relay 233 in the cord circuit CC-1. The supervisory relay in the A operator's circuit which has been described previously as being bridged across the line conductors of the A operator's cord circuit is now included in series with the circuit of the upper and lower windings of relay 233 in the B operator's cord circuit CC-1 and both lower windings of the repeating coil R-1.

Relay 233 energizes over the above-mentioned circuit, but the supervisory relay in the A operator's cord circuit does not energize at this time. Upon energizing, relay 233 closes a circuit for operating relay 232 at armature 237, and at armature 238 it completes a circuit for lighting the supervisory lamp 239 at the B operator's position, thereby informing the B operator that the call is waiting on the associated trunk line. Due to the energization of relay 232, an obvious circuit is completed for relay 230. At armature 231, relay 230 applies ground potential by way of the normally closed contacts controlled by armature 254, jumper on the IDF, conductor 228 and multiples thereof in the banks of the secondary selector switches, such as SS-1 and SS-2, wiper 224 of the secondary selector switch SS-1, over two circuits in parallel. One of these circuits including the holding winding for relay 215, and the other branch of the circuit including conductor 214 and multiples thereof in the banks of the primary selector switches, such as PS-1 and PS-2, test wiper 211, armature 203 and its front contact, winding of the switching relay 202, self-interrupting contacts and winding of the rotary magnet 235, to battery. The return of this ground potential from the cord circuit CC-1 maintains the line relay 215 and the switching relay 202 energized after the removal of ground potential from armature 208 by the deenergization of line relay 206.

It should be understood, however, that due to the fact that the secondary selector switch SS-1 is engaged with an idle cord circuit when the primary selector PS-1 seized the trunk line conductors 212, 213, and 214, that the time interval required for the return of ground on conductor 214 from the cord circuit CC-1 to maintain the line relay of the secondary selector switch and the switching relay of the primary selecting switch energized is a comparatively short interval. Whereas, if the secondary selector switch SS-1 was of the type that would be required to search for an idle cord circuit in a B operator's position after it has been seized by a primary selecting switch, the return of ground potential from the idle cord circuit found by the secondary selector SS-1 would be of considerably greater interval and may be of sufficient length of time to permit the line relay 206 of the primary selector switch to fall back and remove ground potential from the switching relay 202 and the line relay 215 before ground potential is returned from the seized cord circuit. This would result in the deenergization of both the switching relay 202 and line relay 215.

As a further result of the operation of relay 230 in the cord circuit CC-1, the ground potential applied at armature 231 is also extended by way of the IDF and conductor 229 and multiples thereof in the secondary selector switches SS-1 and SS-2, wiper 225 of the secondary switch SS-1, winding of relay 218, to battery. Therefore, as a result of the seizure of cord circuit CC-1 by the secondary selector switch SS-1, ground potential is returned from the seized cord circuit to maintain the line relay 215 of the secondary selector switch SS-1 and the switching relay 202 of the primary selector PS-1 energized and also to complete an energizing circuit for relay 218 of the secondary selector switch SS-1. The operations performed due to the energization of relay 218 will be described hereinafter.

The cord circuit CC-1 at the B operator's position has now been automatically connected to the trunk line selected by the A operator and the B operator attending the group of trunks in which the cord circuit CC-1 is located is connected with the seized cord. The B operator may be automatically connected to the seized cord circuit, or she may be manually connected by a key when she responds to the lighting of lamp 239. The type of cord circuit that is used is of no interest in the present invention and only a portion of the cord circuit has been shown. The dash lines in the line conductors connected to the plug P-1 of the cord circuit CC-1, representing that part of the cord circuit which has not been shown. In any event, as soon as the B operator's telephone instrument is connected with the trunk seized by the distant A operator, a tone signal is automatically transmitted to the A operator to indicate that the B operator is now connected and is ready to receive the number of the wanted subscriber located in her exchange area. When the B operator has received the number of the desired line she tests the called subscriber's line jack in the usual manner and inserts the trunk plug P-1 in order to complete the connection. The ringing of the called subscriber's telephone may be accomplished in any of the well-known ringing schemes by either automatic or manual operation.

When the called subscriber answers, the ringing current is disconnected from the called line in the usual manner which is of no interest in the present invention, and in addition, relay 234

is operated. At armature 262, relay 234 places a shunt circuit around the high-resistance winding of relay 233. In addition, at armature 261, relay 234 causes the supervisory lamp 239 to be extinguished. As a result of the shunting of the high-resistance winding of relay 233, the supervisory relay in the A operator's cord (not shown) receives sufficient current flow in its windings to cause the relay to operate and thereby extinguishes the calling supervisory lamp in the usual manner. Therefore, the answering of a call by the wanted subscriber in the manual office containing the above-mentioned B board, gives the originating A operator the supervisory signal. The extinguishing of the trunk line supervisory lamp 239 is described in the present instance as being responsive to the answering of the called subscriber. However, in some cases the B operator does not receive a signal when the called subscriber answers a call, the trunk lamp at her position responding only to the A operator's seizing of a cord circuit or disconnecting therefrom.

The connection is now completed between the calling subscriber in the area served by the manual office at which the A board is located and the called subscriber served by the manual office in which the B board is located. The talking conductors of the circuit shown in Fig. 2 include the trunk line T-1, armatures 204 and 205, the associated front contacts of relay 202, wipers 209 and 210, conductors 212 and 213 of the secondary selector switch SS-1, front contact controlled by armature 217, wipers 222 and 223, conductors 226 and 227 cross connected at the IDF to the lower winding of the repeating coil R-1. The battery feed for talking purposes being connected to this circuit in the A operator's cord. The called end of the talking connection is completed through the upper winding of the repeating coil R-1, and the tip and ring conductors connected to the plug P-1. The talking current for this circuit being connected in the B operator's cord circuit equipment (not shown).

Referring again to the seizure of the cord circuit CC-1 by the A operator and the resulting transmission of a tone signal to the A operator to indicate to her that the B operator is connected. At this time the common equipment associated with position 1 at the B board, is also controlled and ground potential is applied to conductor 259 causing the operation of relay 253. Accordingly, when the B operator at position 1 is idle, any one of the cord circuits at her position is seizable by an A operator. It is understood, however, that if a call is set up over any one of the cord circuits in the B operator's position, a ground potential is applied to test conductors, such as 228 and 229 by way of armature 231 of the operated relay 230. This relay is maintained energized throughout the entire connection established over any one of the cord circuits. When a connection is set up over a cord circuit, such as cord circuit CC-1, the operator is again available to receive another call over any other cord circuit.

During the interval required for the B operator to receive the wanted subscriber's number and also to set up the connection to the wanted subscriber's line, provisions are made in the common equipment of the particular B operator's position for busying all the remaining cord circuits at her position until she is again available to establish further connections. This is accomplished as mentioned above, by the grounding of conductor 259 during the time she is answering and setting up a call received over one of her cord

circuits. The armatures 254 and 255 controlled by relay 253, are shown connected to the test conductors 228 and 265, respectively, while armature 256 is drawn to represent the remaining 5 cord circuits at position 1 of the B operator's board. When relay 253 is operated, armatures 254, 255, and 256 and any other of such armatures of other cord circuits (not shown) at position 1 are all operated to engage their associated 10 front contacts and to disengage the normally closed contact controlled by the front contact of these armatures. In the cord circuit CC-1, the ground at armature 254 is connected by way of its front contact of conductor 228 and since this cord 15 circuit is the one that has been used in establishing the above-described connection, the ground potential at armature 254 is merely substituted for the ground potential applied by way of armature 231 to maintain the line relay 215 of the secondary selector SS-1 and the switching relay 202 of the primary selector PS-1 energized. However, at armature 255 of the cord circuit CC-2 of position 1, (relay 230' is not energized due to the fact that this cord circuit is not in use) ground potential is applied by way of test 20 conductor 265 to the banks of the secondary selector SS-2 and all other secondary selectors in the group having access to the cord circuit CC-2 by way of the bank multiple. This ground potential applied to test conductor 265 prevents a 25 primary selector from seizing an idle secondary selector whose wipers are engaging the bussed cord circuit, due to the fact that the ground potential is then extended through the connected 30 test wiper, such as 224', to a test conductor, such as 214', in the banks of the primary selector switches, it being understood that armature 256 and all other armatures similar to armature 256 of the remaining cord circuits at position 1 of the B operator's board also apply ground potential to the test banks of the secondary selector 35 switches having access thereto.

Referring again to relay 218 of the secondary selector switch SS-1, it will be noted that when all of the secondary selector switches in a group are idle that a chain circuit is normally completed from ground at armature 220, resistance 236, resistance 236' of the secondary selector switch SS-2, and in series with similar resistances of all the remaining secondary selectors in the same group, through the winding of marginal relay 244, to battery. Due to the total resistance in this chain circuit, relay 244 does not receive sufficient current to energize. Attention 40 is called to the fact that each group of secondary switches is provided with a similar series circuit for a marginal relay, similar to marginal relay 244, the functions of which will be apparent from the following description.

It will be recalled that when the cord circuit CC-1 was seized by secondary selector switch SS-1, that ground potential was returned on conductor 229 and multiples thereof, to cause the energization of relay 218. Therefore, if the 45 wipers of several of the secondary selector switches in the same group are also standing on bank contacts to which the conductors of cord circuit CC-1 are multiplied, the relays, such as relay 218, in such secondary selector switches are also energized from the same ground potential returned over conductor 229. At armature 219, relay 218 prepares a circuit for the rotary magnet 221, and at armature 220 it shunts out the resistance 236 of the chain circuit for the marginal 50 relay 244.

It will now be assumed that the wipers 222' to 225' of the secondary selector switch SS-2 are standing on the bank contacts to which the conductors 226-229 of the cord circuit CC-1 are multiplied. Therefore, the ground potential returned on conductor 229 and multiples thereof by the cord circuit CC-1 causes the operation of relay 218' of the secondary selector switch SS-2. Relay 218' upon energizing prepares a similar circuit for its rotary magnet 221' at armature 219', and at armature 220' it shunts out the resistance 236' of the chain circuit for marginal relay 244. It will be apparent from the above description that any other secondary selector switches in the group, having their wipers resting on the bank contacts to which the trunk conductors of the cord circuit CC-1 are multiplied, the relays corresponding to relays 218 and 218' will be energized and prepare the circuits for their associated rotary magnets and also shunt out resistances, similar to resistances 236 and 236'. When sufficient of these resistances have been shunted out of the chain circuit for the marginal relay 244 sufficient current will flow through the winding of the relay to cause it to energize. Attention is called to the fact that the ground potential returned from the cord circuit CC-1 over the conductor 229 and multiples thereof to cause the operations of relays, similar to 218, of all secondary selectors whose wipers are standing on the trunk multiples of the cord circuit, is also returned over conductor 228 and multiples thereof in the banks of all the secondary selectors in the group. In the secondary selector switch SS-1, the one over which the call is extended, this ground potential provides a holding circuit for the line relay 215 and the switching relay 202, as has previously been mentioned, whereas in the secondary selectors over which no calls are extended and whose wipers are standing on the trunk multiples of the cord circuit CC-1, this ground potential is extended by way of wipers, similar to wiper 224' of secondary selector switch SS-2, and conductors, similar to conductor 214', to the banks of primary selector switches, similar to primary selector switch PS-2. This ground potential is returned on conductor 214' and all similar test conductors of other secondary selector switches in group 1 to busy these secondary selector switches in the banks of the primary selector switches having access thereto.

In order to prevent the primary selector switches from having to search over too many busy bank contacts, the above-mentioned chain circuit for the marginal relay 244 is provided to reset the idle secondary selector switches that are standing on bank contacts of busy cord circuits to pre-select idle cord circuits so that the primary selectors will not have to search any appreciable time to find an idle trunk line extending to a secondary selector switch and cord circuit.

Referring again to the operation of the marginal relay 244, it will be noted that at armature 245 it completes an energizing circuit for relay 240. Relay 240, upon energizing, closes the front contacts of armatures 241, 242, and 243, and all similar armatures of other secondary selector switches in the same group. Due to the fact that line relay 215 of secondary selector switch SS-1 is energized, the closing of armature 241 has no effect upon the rotary magnet 221 because the circuit is opened at armature 216 and its back contact. At armature 242, however, the ground potential applied to conductor 214' by way 75

of test wiper 224' which is assumed to be standing on bank contacts to which the busy cord circuit CC-1 is a multiple, completes a circuit for the rotary magnet 221' by way of armature 219' of the energized relay 218'. Rotary magnet 221' interrupts its own circuit and advances its wipers 221' to 225' one step to the next bank contact. If the cord circuit connected to the next bank contact is idle, the ground potential is removed from the wiper 224' and the wipers come to rest on the cord circuit connected to these bank contacts. If the cord circuit connected to this bank contact is busy, a ground potential will be encountered by the test wiper 224' and cause the rotary magnet to again energize and advance the wipers another step. In this manner, the secondary selector switch SS-2 advances its wipers until an idle cord circuit is found, thereby preselecting an idle cord circuit so that it is available to a primary selector switch. Armature 243 and all other armatures, similar to armature 243, of other secondary selector switches close the above circuit described in connection with secondary selector switch SS-2 and accordingly control these secondary selector switches to pre-select an idle cord circuit.

When the wipers of the secondary selector switch SS-2 have been advanced to an idle cord circuit, relay 218' deenergizes and opens the step-ping circuit for the rotary magnet at armature 219' and removes the shunting circuit for resistance 236' at armature 220'. The remaining secondary selector switches that have advanced their wipers to idle cord circuits are also controlled in the same manner described in connection with selector switch SS-2. In this manner, resistances are again inserted in the chain circuit for the marginal relay 244 and the relay eventually falls back and opens the circuit for relay 240 at armature 245. Relay 240 falls back and opens the circuits closed at the front contacts of armatures 241, 242, and 243 and all other similar armatures of other secondary selector switches (not shown).

It may be well to mention at this time that as long as the B operator at position 1 is busily engaged in setting up a connection of the type previously described over a cord circuit CC-1, the energization of relay 253 which busies all of the cord circuits at her position, does not prevent the secondary selector switches such as SS-2, from selecting a cord circuit at her position when their wipers are automatically rotated to preselect an idle cord circuit. The temporary busying of the cord circuits at the B operator's position that is extending a connection is only for the purpose of preventing a primary selector from extending a call to her position while she is busy. This arrangement causes the primary selectors to rotate and find an idle cord circuit at another B operator's position. However, as soon as the B operator has completed the connection, referred to above, relay 253 restores to normal and removes the busying potential from the cord circuits at her position that are available for additional calls.

Referring again to the connection established over cord circuit CC-1, it will be remembered that when the called subscriber answered the supervisory lamp 239 was extinguished. When the conversation is completed between the calling and the called subscribers, the hanging up of the called subscriber causes the relay 234 to fall back. At armature 262, relay 234 removes the shunt 75 from around the high resistance lower winding

of relay 233. Due to the fact that the high resistance of the lower winding of relay 233 is again inserted in the loop circuit including the lower windings of the repeating coil R1 and the supervisory relay in the A operator's cord circuit, the supervisory relay in the A operator's cord circuit deenergizes and lights the supervisory lamp at her position to give the disconnect signal. In addition, the hanging up of the calling subscriber lights the answering lamp at the A operator's position, thereby informing her that the conversation between the calling and the called subscriber has been terminated. In the B operator's position the trunk lamp 239 is lighted when the called subscriber hangs up and relay 234 is released, to indicate to the B operator that the called subscriber has hung up his receiver and the connection is about to be taken down by the A operator. However, it is to be understood that this is a representation of one type of supervision for the B operator and that in other types of cord circuits the B operator does not receive any supervision on the hanging up of the called subscriber, but only receives disconnect supervision when the A operator pulls down the connection.

The A operator takes down the connection by removing the plug of her cord circuit from the jack JK-1, thereby releasing the sleeve relay 291 and all other sleeve relays of jacks to which the trunk line T-1 is multiplied. The release of the sleeve relays extinguishes the lamps at all the positions to which this trunk line is multiplied to indicate to the operators at these positions that this trunk line is again available for the extension of calls. When the connection is broken down by removal of the plug by the A operator, relay 233 in the cord circuit CC-1 falls back and extinguishes the lamp 239. At armature 231, relay 233 opens the circuit for relay 232 which relay, upon falling back, opens the circuit for relay 239. When the B operator receives the disconnect signal she removes her plug P1 from the called subscriber's line jack. The release of relay 230 removes ground potential from conductors 228 and 229 and multiplies thereof in the banks of the secondary selector switches. When ground is removed from conductor 229, relay 218 falls back and again inserts the resistance 236 in the chain circuit of the marginal relay 244. The removal of ground from conductor 228, wiper 224, and conductor 214, permits line relay 215 of the secondary selector switch SS-1 to restore to normal and in addition removes the holding ground from the switching relay 202. The deenergization of relay 215 restores the secondary selector switch SS-1 to normal and the deenergization of switching relay 202 restores the primary selector switch PS-1 to normal. The trunk line and cord circuit T-1 and CC-1, respectively, together with the primary selector PS-1 and the secondary selector SS-1, are now available for the extension of other calls.

A description will now be given of the redistribution of secondary selector switches to pre-select idle cord circuits when one of the positions of the B operator's switchboard is vacated for any reason whatsoever. When an operator leaves her position, ground potential is applied to conductor 260 of the common equipment at her position, causing the operation of relay 243. At armature 249, relay 248 places a ground potential on conductor 229, and in addition, by way of the normally closed contacts controlled by 75

armature 254 it places a ground potential on conductor 228. At armature 250, relay 248 places ground potential on conductor 266, and by way of the normally closed contacts controlled by armature 255 it places ground potential on conductor 265. This ground potential is extended by way of the multiples of these conductors to other secondary selector switches in the group in which selector switches SS-1 and SS-2 are located. In addition, armature 251 and all other armatures similar to armature 251, of the cord circuits not shown in the drawings, extend ground potential to the banks of the associated secondary selector switches in the same manner as described in connection with armatures 249 and 250 of cord circuits CC-1 and CC-2. In the secondary selector switch SS-1 relay 218 is energized due to the fact that its wiper 225 is standing on the bank contact to which grounded conductor 229 is connected. In addition, the ground potential applied to conductor 228 is extended by way of wiper 224 to conductor 214. The energization of relay 218 prepares a circuit for rotary magnet 221 at armature 219 and shunts the resistance 236 from the chain circuit of the marginal relay 224 by the closing of armature 220 and its front contact.

In the secondary selector SS-2 the wipers 222' to 225', inclusive, are shown standing on the first set of bank contacts. It will be assumed, that the trunk conductors 226 to 229, which are connected to the first set of bank contacts of the secondary selector switch SS-1, are also multiplied to the first set of bank contacts of the secondary selector switch SS-2. This being the case, the ground potential applied to conductors 228 and 229 is extended to the bank contacts upon which the wipers 224' and 225' of the secondary selector switch SS-2 are standing. Therefore, the relay 218' is energized and the conductor 214' is grounded. The energization of relay 218' prepares a circuit for the rotary magnet 221' at armature 219', and at armature 220' the resistance 236' is shunted from the chain circuit for the marginal relay 244.

The operation of armature 250, responsive to the energization of relay 248, applies ground potential to conductors 265 and 266 and multiples thereof terminating in the banks of the secondary selector SS-2 and other secondary selector switches in the same group of switches in which the secondary selector SS-2 is located. Inasmuch as the wipers of the secondary selector switches SS-1 and SS-2 are not standing on the bank contacts to which these conductors are multiplied, nothing occurs in these two selector switches. However, it may be assumed that other selector switches in the same group have wipers standing on bank contacts to which these conductors are multiplied, in which case, the relays, similar to relay 218', located in these secondary selectors are operated in the same manner as described in connection with the operation of relay 218 of secondary selector switch SS-1 and relay 218' of secondary selector switch SS-2. The operation of these relays will cause the resistances, similar to resistances 236 and 236', to be shunted out of the chain circuit for the marginal relay 244 and in addition, will prepare the energizing circuit for their respective rotary magnets, similar to rotary magnets 221 and 221'.

As has been previously described, the shunting of the resistances in the chain circuit for the marginal relay 244 eventually causes the relay 240 to operate and complete the energizing circuit

for relay 240. Relay 240, upon energizing, closes the front contacts of armatures 241, 242, and 243, and all similar armatures. When the front contact of armature 241 is closed, the ground potential applied to conductor 214 is extended by way of armature 216 and its resting contact, armature 241 and its front contact, armature 219 of the energized relay 218, self-interrupting springs and winding of the rotary magnet 221, to battery. In addition, the closing of front contact of armature 242 extends the ground potential applied to conductor 214' by way of wiper 224' and the bank multiple connected to conductor 228, by way of the lower armature and resting contact of relay 215', armature 242 and its front contact, armature 219' and its front contact, self-interrupting springs and winding of the rotary magnet 221', to battery. The ground potential applied to conductor 265 and multiples thereof of other secondary selector switches, similar to SS-2, will also cause the operation of the rotary magnets of any of the secondary selector switches (not shown) having their wipers standing on bank contacts to which this trunk conductor is multiplied. It should be understood, however, that the wipers of some of the secondary selector switches, in the group of selector switches referred to above, may be connected to bank contacts terminating cord circuits in other positions of the B board, in which case, the test wipers, similar to wipers 224 and 225, are not grounded. Consequently the relays similar to relay 218, are not energized, and the operation of armatures, similar to 243, will have no effect when such a condition is encountered.

The rotary magnets of the secondary selector switches in which the relays, similar to relays 218 and 218', are energized, advance their wipers until they engage idle cord circuits.

As soon as the rotary magnet 221 of secondary selector switch SS-1 has advanced its wipers 222-225, inclusive, to a set of bank contacts to which an idle cord circuit is connected, relay 218 is deenergized and opens the rotary magnet circuit at armature 219 and again connects the resistance 236 in the chain circuit of the marginal relay 244. The wipers 222'-225', inclusive, of secondary selector switch SS-2, which is controlled by the rotary magnet 221', may not have found an idle cord circuit as soon as the wipers of the secondary selector switch SS-1. If other secondary selector switches in the same group in which secondary selector switch SS-1 is located have advanced their wipers and have found idle cord circuits, sufficient resistance may be again inserted in the chain circuit for the marginal relay 244 to cause the same to fall back and open the circuit of relay 240. This may occur when the wipers of the secondary selector switch SS-2 are still standing on the bank contacts of a trunk connected to one of the cord circuits of a vacated B operator's position.

It will be assumed, for the purpose of describing such a condition, that the wipers 222' to 225', inclusive, have been advanced to the set of bank contacts to which conductors 263 to 266, inclusive, are connected when the marginal relay 244 and relay 240 are deenergized. In the secondary selector switch SS-2, relay 218' will be maintained energized from the ground potential applied at armature 250 and the conductor 214' will be grounded from the same source. The circuit for rotary magnet 221', however, will be opened at armature 242 due to the fact that the relay 240 has restored to normal. Therefore, 75

the wipers of the secondary selector switch SS-2 will come to rest in engagement with a busy cord circuit of a vacated B operator's position. However, the ground potential applied to conductor 214' and multiples thereof in the banks of the primary selectors, prevents the primary selectors from seizing the secondary selector switch SS-2 as long as conductor 214' is grounded. Inasmuch as the secondary selector switches in the group shown on the drawings have been advanced and have preselected other cord circuits at B operators' positions that have not been vacated, the fact that a few of the secondary selectors in the group are still in engagement with cord circuits extending to the vacated B operator's position does not create any congestion in trunking, due to the fact that the primary selectors will have sufficient outlets to cord circuits of the attended B operators' positions.

From the foregoing description of the busying of all the cord circuits at a vacated B operator's position, it will be understood that the secondary selector switches having access to these cord circuits will not preselect any of them as long as the cord circuits are busied by the operation of the relay 248. Therefore, the calls that have previously been extended to these vacated B operators' positions will now be redistributed amongst the remaining B operators at the switchboard. If some of the secondary selector switches are still positioned with their wipers engaging the busied cord circuit of the vacated operator's position, the primary selector switches will be unable to seize these secondary selectors due to the fact that the test conductors, similar to 214 and 214', will have a ground potential applied to them. It should also be understood that if the B operator's position is vacated for any length of time, that the secondary selector switches having access to these cord circuits will eventually preselect idle cord circuits in attended B operators' positions. Therefore, when the B operator returns to the vacated position and is ready to again extend calls through her position, no calls will be coming in to her position due to the fact that the secondary selector switches have preselected idle cord circuits in the remaining B operators' positions. To eliminate any delay in again having calls distributed to the vacated position when it is again made available, the circuit arrangement about to be described is provided to redistribute the traffic to the now attended B operators' positions.

It will be remembered that when the B operator vacated her position that relay 248 was energized over a circuit including conductor 260 and in response to the energization of relay 248, in addition to busying all of the cord circuits at the B operator's position by closing armatures 249, 250, 251, and other similar armatures not shown, slow-to-release relay 246 is energized from ground by way of the front contact of armature 252. When the absent B operator returns to her position she causes ground potential to be removed from conductor 260, thereby opening the energizing circuit to relay 248. Relay 248 restores to normal and removes the busy ground potential from all the cord circuits at her position and at armature 252 and its front contact opens the energizing circuit for relay 246. However, due to the fact that relay 246 is somewhat slow to release, a circuit is now completed by way of the back contact of armature 252, front contact of armature 247, through the winding of relay 265 which accordingly energizes. At-

tention is called to the fact that relay 265 is common to all B operators' positions and is operated in the manner described above from any position that has been vacated and again put into operation by the return of the operator. At armature 266, relay 265 completes an energizing circuit for relay 240 which relay is common to all secondary selectors in group 1. At armature 267 and similar armatures (not shown) relay 265 completes energizing circuits for relays, similar to relay 240, individual to each group of secondary selector switches. Responsive to the energization of relay 240, at armatures 241, 242, 243, and all other similar armatures of the secondary selector switches in the group including SS-1 and SS-2, it prepares a circuit for each of the rotary magnets of these secondary selector switches in the same manner as has been previously described. It will be remembered that in the previous description of operation that takes place when the B operator's position is vacated, that the rotary magnets of the secondary selectors were automatically operated in order to select idle cord circuits in other B positions. In addition, it was also pointed out that some of the secondary selector switches may still be connected to cord circuits of vacated B operators' positions.

It will be assumed in the present description, however, that some of the secondary selectors of the group have preselected other cord circuits than those connected to the vacated B operator's position, and that other secondary selector switches in the group are standing on busy cord circuits, and have not been advanced due to the fact that sufficient of the resistances, similar to resistances 236 and 236' have not been shunted out of the circuit of the marginal relay 244. The secondary selector switches that have their associated test wipers, similar to wipers 224 and 225, standing on bank contacts grounded by some cord circuit being used in extending a connection, will have a relay, similar to relay 218, energized and their line relays will not be energized. It is understood, however, that if any secondary selector switch is being used in the extension of a call that the line relay, similar to line relay 215 will be energized and be locked up by way of its lower winding to the grounded test conductor, similar to conductor 214.

Assuming that some of the selectors are standing on busy contacts and the line relays are not energized, the previously traced interrupting circuit for each rotary magnet (completed by the energization of relay 240) and will advance the wipers step by step until idle cord circuits are found. When an idle cord circuit is found, ground potential will not be encountered on the test bank contacts and the test relay, similar to 218, will fall back and open the rotary magnet circuit. Since the cord circuits at the vacated B operator's position are again available, some of the secondary selector switches select idle cord circuits in this position.

Shortly after the above-described deenergization of relay 248, slow-to-release relay 246 also falls back and again opens the circuit for relay 240 common to secondary group 1, and all other similar relays common to other secondary groups. Relay 240 falls back and opens the front contacts of armatures 241, 242, 243, and all other similar armatures for controlling the automatic stepping of secondary selector switches in group 1.

In the description thus far we have assumed

that the cord circuits, such as CC-1 and CC-2, are located in position 1 of the B operator's board. However, it should be clearly understood that the cord circuits at position 1 may be cross-connected at the intermediate distributing frame IDF so that all groups of secondary selectors have access to cord circuits in this position. Therefore, when a B operator vacates a position, a relay, such as 248, is energized as previously described to busy all of the cords at the vacated position. When the B operator returns and causes the release of the relay, such as 248, a slow-to-release relay, such as 246, completes a circuit for the common relay 265. The diagonal line shown to the right of the relay indicates that this relay is common to all B operators' positions. In response to the energization of relay 265, a circuit is closed at armature 266 for energizing relay 240, which relay is common to the group of secondary selector switches shown on the drawings. In addition, at armature 267, relay 265 completes a circuit for a relay, similar to relay 240, in the next group of secondary selector switches. It is to be understood that relay 265 may have other armatures on its spring assembly whereby ground is extended to control relays, similar to relay 240, of additional groups of secondary selector switches in which any of the cord circuits of the various B operators' positions are accessible.

30 In addition, it will be understood that marginal relays are also connected, in the same manner as relay 244, to their respective groups of secondary selector switches. When any one of the marginal relays is operated due to the shunting out of sufficient resistances, such as 236 a relay, such as 240, is energized, thereby controlling the automatic stepping of the secondary selector switches of its group that have wipers standing on bank contacts of busy cord circuits.

40 From the foregoing description it is seen that the present invention makes it possible to secure efficient distribution of calls from an A operator's switchboard in one manual exchange to a B operator's position in a manual switchboard in a second exchange.

45 Having fully described the invention, what is considered new and is desired to have protected by Letters Patent will be pointed out in the appended claims.

50 What is claimed is:

1. In a telephone system, a plurality of trunk lines connected to multiple jacks in a plurality of A operators' positions, a first group of automatic primary trunking switches in which said trunk lines terminate, a second plurality of trunk lines connected to different multiple jacks in said plurality of A operators' positions, a second group of automatic primary trunking switches in which said second plurality of trunk lines terminate, a first and second group of automatic secondary trunking switches, an individual secondary trunk line terminating in each switch of said groups of secondary switches, the individual secondary trunk lines terminating in switches of said first group of secondary switches accessible to all of the switches in said first primary group, the individual secondary trunk lines terminating in switches of said second group of secondary switches accessible to all of the switches in said second primary group, a B operator's switchboard comprising a plurality of positions, a plurality of cord circuits for each of said positions, an individual trunk line for each of said cord circuits, one of the cord circuits at each one of said B operators' positions accessible by way of its indi-

vidual trunk line to all of the switches in the first of said secondary groups, and another one of the cord circuits at each one of said B operators' positions accessible by way of its associated trunk line to all of the switches in the second of said secondary groups.

2. In a telephone system, a first and a second manual office, inter-office trunk lines connecting said offices, a plurality of A operators' positions at said first office for receiving and extending calls to said second office, a plurality of B operators' positions at said second office for completing incoming calls from said first office, primary and secondary selector switches at said second office, said primary switches terminating the trunk lines from said first office, cord circuits at each of said B operators' positions, said secondary switches having access to and means for preselecting said cord circuits, means in said primary switches operated responsive to the seizure of one of said inter-office trunk lines by one of said A operators for automatically selecting an idle cord circuit preselected by any one of said secondary switches.

3. In a telephone system in which straightforward trunking is provided to extend calls from A operators' positions in one manual exchange to B operators' cord circuits in another manual exchange, primary and secondary selector switches at the exchange in which said B operators' switchboard is located, trunk lines extending between said exchanges seizable by the A operators to extend calls, said trunk lines terminating in said primary selectors, means in said primary selectors operated responsive to the seizure thereof by an A operator over any one of said trunk lines for extending the trunk line used through said seized primary selector to one of said secondary selectors to seize the same, said secondary selectors having access to said B operators' cord circuits, and means in said seized secondary selector operated responsive to the seizure thereof for extending the said trunk line through said seized secondary selector to an idle cord circuit of one of said B operators' positions.

4. In a telephone system in which straightforward trunking is provided to extend calls from A operators' positions in one manual exchange to B operators' cord circuits in another manual exchange, primary and secondary selector switches at the exchange in which said B operators' switchboard is located, trunk lines extending between said exchanges seizable by the A operators to extend calls, said trunk lines terminating in said primary selectors, means in said primary selectors operated responsive to the seizure thereof by an A operator over any one of said trunk lines for extending the trunk line used through said seized primary selector to one of said secondary selectors to seize the same, said secondary selectors having access to said B operators' cord circuits, means in said seized secondary selector operated responsive to the seizure thereof for extending the said trunk line through said seized secondary selector to an idle cord circuit of one of said B operators' positions, and means in said seized primary selector for preventing any other of said primary selectors from being operated to seize the same secondary selector used to extend the said trunk line to an idle cord circuit and for maintaining said secondary selector in seized condition.

5. In a telephone system in which straightforward trunking is provided to extend calls from A operators' positions in one manual exchange to

- B operators' cord circuits in another manual exchange, primary and secondary selector switches at the exchange in which said B operators' switch-board is located, trunk lines extending between 5 said exchanges seizable by the A operators to extend calls, said trunk lines terminating in said primary selectors, means in said primary selectors operated responsive to the seizure thereof by an A operator over any one of said trunk lines 10 for extending the trunk line used through said seized primary selector to one of said secondary selectors to seize the same, said secondary selectors having access to said B operators' cord circuits, means in said seized secondary selector 15 operated responsive to the seizure thereof for extending the said trunk line through said seized secondary selector to an idle cord circuit of one of said B operators' positions, and means in said cord circuit operated responsive to the extension 20 of said trunk line thereto for identifying that cord circuit by means of a signal, for preventing the seizure of said cord circuit by any other secondary selector, for preventing the seizure of the seized secondary switch by any other primary selector, and for maintaining the primary 25 and secondary selector used in extending the trunk line to the cord circuit in seized condition.

6. In a telephone system, a plurality of A operators' positions, a B operator's position, cord 30 circuits at said B operator's position, selectors over which said A operators extend connections having access to said cord circuits, means in each of said cord circuits operated responsive to the extension of a connection to any one of them 35 from said A operators via one of said selectors for preventing further seizure of said one cord circuit by any other of said selectors, means common to all of said cord circuits operated during the time said B operator is setting up 40 the connection received over said one cord circuit for preventing any other connections from said A operators from being received at said B operator's position.

7. In a telephone system, a plurality of 45 switches, a chain circuit including all of said switches, a resistance in each of said switches included in said chain circuit, a normally de-energized relay connected to said chain circuit, means in each of said switches for shunting its 50 associated resistance out of said chain circuit, said common relay energizing when a predetermined number of resistances have been shunted out of said chain circuit by said switches, and means controlled by said common relay for preparing an automatic stepping circuit for each of 55 said switches.

8. In a telephone system including an A operator's position and a B operator's position, trunk 60 lines interconnecting said positions, A operator's means for extending calls over said trunk lines, cord circuits at said B operator's position, cord selecting means terminating each of said trunk lines, cord determining means interposed between each of said cord selecting means and each of 65 said cord circuits for preselecting the cord circuits for each of said selecting means, and means at said B operator's position operated after a call is received over one of her cord circuits for preventing the selection of preselected cord circuits 70 by any of said cord selecting means until that call is extended while permitting any of said cord determining means to preselect other cord circuits at her position.

9. In a telephone system, a B operator's position, a plurality of cord circuits at said position,

a plurality of groups of non-numerical switches, each of the switches in each of said groups having access to a different cord circuit, means for extending a call, via one of said switches and the cord circuit individual to the group of switches 5 in which said one switch is located, to said position, and means responsive to the extension of said call to said position for preventing the extension of further calls to said position via any of the other switches in said groups of switches 10 until that call is extended.

10. In a telephone system, a plurality of switches, a like plurality of associated wiper sets, bank contacts over which the wipers of said switches extend connections, a plurality of operators' cord circuits multiplied to the bank contacts of each of said switches, each of said switches having access to said cord circuits via said wipers and bank contacts, means for seizing any one of said switches to operatively connect 15 with one of said cord circuits via an associated wiper set, each of said wiper sets including a test wiper and an auxiliary test wiper, means in the connected cord circuit operated responsive to a connection for extending circuits to any of said 20 switches having test wipers and auxiliary test wipers of the wiper sets engaging bank contacts to which the selected cord is multiplied to prevent the seizure of any other of said switches and to prepare stepping circuits for such switches, and 25 means responsive when said last-mentioned circuits are extended via both of said test wipers to a predetermined number of said switches for controlling said stepping circuits to disconnect their associated wiper sets from the bank contacts to 30 which said connected cord circuit is multiplied.

11. In a telephone system, a plurality of switches, a like plurality of associated wiper sets, bank contacts over which the wipers of said switches extend connections, a plurality of operators' cord circuits multiplied to the bank contacts of each of said switches, each of said switches having access to said cord circuits via 35 said wipers and bank contacts, means for seizing any one of said switches to operatively connect 40 with one of said cord circuits via an associated wiper set, each of said wiper sets including a test wiper and an auxiliary test wiper, means in the connected cord circuit operated responsive to a connection for extending circuits to any of said 45 switches having test wipers and auxiliary test wipers of the wiper sets engaging bank contacts to which the selected cord is multiplied to prevent the seizure of any other of said switches and to 50 prepare stepping circuits for such switches, and 55 means responsive when said last mentioned circuits are extended via both of said test wipers to a predetermined number of said switches for controlling said stepping circuits to disconnect their associated wiper sets from the bank contacts to 60 which said connected cord circuit is multiplied, said last mentioned means also effective responsive to some of said predetermined number of switches disconnecting associated wiper sets from multiples of said connected cord to prevent other switches of said predetermined number from disconnecting their associated wiper sets from multiples of said connected cord.

12. In a telephone exchange system, a first operator's position, calling jacks therefor, a trunk 65 finder directly connected to each of said jacks, a second operator's position, cord circuits at said second operator's position, preselecting secondary selector switches connected to idle cord circuits, said secondary selector switches accessible by way 70

- of bank contacts of said finders, means responsive when the operator at said first position extends a connection by plugging into one of said jacks for controlling the associated finder switch 5 to extend the connection by way of its bank contacts to any secondary selector switch that has preselected an idle cord circuit, and means operated in the secondary selector switch to which the connection is extended for further extending the 10 connection through to said preselected cord circuit.
13. In a telephone exchange system, a first operator's position, calling jacks therefor, a trunk finder directly connected to each of said jacks, 15 a second operator's position, cord circuits at said second operator's position, preselecting secondary selector switches connected to idle cord circuits, said secondary selector switches accessible by way of bank contacts of said finders, means responsive 20 when the operator at said first position extends a connection by plugging into one of said jacks for controlling the associated finder switch to extend the connection by way of its bank contacts to any secondary selector switch that has preselected an 25 idle cord circuit, means operated in the secondary selector switch to which the connection is extended for further extending the connection through to said preselected cord circuit, and means common to all of said cord circuits for 30 placing a busy potential by way of said preselecting secondary selectors on the banks of said finder switches to prevent any of said finder switches from operatively connecting with any of said cord circuits, when one of the cord circuits is being 35 used to extend a connection.
14. In a telephone system, a group of cord circuits, a preselecting switch temporarily associated with each of the cord circuits of said group, an incoming trunk for each of said preselecting 40 switches, hunting switches for selecting said trunks and associated preselecting switches to extend connections to any one of said cord circuits, means responsive to the extension of a connection to one of said cord circuits for preventing the seizure of another trunk by any of 45 said hunting switches, a second group of cord circuits, and means in said preselecting switches operated responsive to the extension of the connection to said one cord circuit for controlling 50 said preselecting switching to select cord circuits in said second group of cord circuits to thereby permit said hunting switches to extend connections only to cord circuits in said second group of cords.
- 55 15. In a telephone system, a plurality of incoming lines, a primary selector terminating each of said incoming lines, primary trunk lines accessible to said primary selectors, a preselecting secondary selector switch individual to each of said primary trunk lines, secondary trunk lines accessible to said secondary selectors, cord circuits individual to each of said secondary trunk lines, said primary trunks characterized as unselectable by the presence of a potential and characterized 60 as selectable by the absence of a potential, means for operating said primary switch over an incoming line to thereby select a primary trunk line characterized by the absence of said potential and connected via a preselecting secondary switch 65 to an idle cord circuit, and means in said preselected cord circuits for controlling the application of the potential to said primary trunks when said cord circuits are not selectable.
16. In a telephone system, a plurality of operators' positions, cord circuits individual to each of said positions, switches adapted to preselect idle cord circuits at said positions, means operated responsive to incoming calls for finding and 5 extending the calls to preselected cord circuits, means at an operator's position operated when said position is vacated for preventing the finding means from connecting with preselected cord circuits at said position, means common to said 10 switches operated only when a predetermined number of switches are engaging cord circuits at a vacated position by controlling a portion of said predetermined number of switches to preselect idle cord circuits at an attended position. 15
17. In a telephone system, a plurality of cord circuits, rotary switches and associated bank contacts, said switches arranged to preselect said cord circuits by way of said bank contacts, means for seizing said switches to extend connections to said cord circuits, means common to said cord circuits operated as long as an operator is answering a connection received over one of said cord circuits for busying all of said cord circuits to thereby prevent said seizing means from extending connections to any of said cord circuits and for controlling a certain percentage of said rotary switches to disconnect from the cord circuits that are not attended. 20
18. In a telephone system, a plurality of operators' positions, a plurality of cord circuits at each of said positions, means individual to each position for preventing incoming calls from being received by any cord circuit thereat while an operator is extending a call received over one 30 of the cord circuits, a second individual means at each position for busying all of the cord circuits at a position during the time that said position is vacated to thereby prevent any incoming calls from connecting with a cord circuit at said vacated position, distributor switches normally engaging idle cord circuits at said positions, and means, in the switches connected to cord circuits of a vacated position, operated by the second individual means for controlling a 40 percentage of the switches connected to cord circuits of a vacated position to cause them to engage idle cord circuits at attended positions. 45
19. In a telephone system, a plurality of operators' positions, a plurality of cord circuits 55 for each of said positions, a plurality of switches connected to cord circuits at both of said positions, means at each position for busying all the cord circuits thereat during the time that the position is vacated and for removing the busy 60 condition from the cord circuits thereat when the position is again attended, means common to said switches for controlling a percentage of the switches connected to bussed cord circuits of said vacated position to select idle cord circuits at the attended positions, and means common to all positions operated momentarily when said vacated position is again attended for controlling switches connected to cord circuits at the remaining positions to connect with idle cord 65 circuits at the again attended position. 70
